Samuel H. Sailor of Philadelphia, Pa.
Ass't to Warnick, Leibrandt & Co,
Letters Patent No. 351. Dated Feb^Y 25, 1851.

The Schedule referred to in these Letters Patent and making part of the same.

To all whom it may concern:

Be it known that I, Samuel H. Sailor of the District of Kensington, County of Philadelphia, State of Pennsylvania, Barber, have invented or produced a new design for Cooking Stoves, And I do hereby declare that the following is a full and exact description of the same:

The design consists in the application to stoves, with suitable mouldings, of an ornament formed by combining rays with an eye and ribbon, as represented in the accompanying drawings, in which Fig. 1 is a side elevation of the stove, Fig. 2 a front elevation, and Fig. 3 a back elevation.

c represents the ornaments of the large oven door.

d " " " of the small oven door.

e " " " of the fire box door.

What I claim as my invention and wish to secure by letters patent, is the application of the above design to Cooking Stoves.
